CHARLES C. SCHARPENBERG, OF BAKERSFIELD, CALIFORNIA.

GAS-TRAP.

1,226,913.

Specification of Letters Patent.

Patented May 22, 1917.

Application filed August 2, 1916. Serial No. 112,673.

To all whom it may concern:

Be it known that I, CHARLES C. SCHARPENBERG, a citizen of the United States, residing at Bakersfield, in the county of Kern and State of California, have invented a new and useful Gas-Trap, of which the following is a specification.

It is the object of my invention to produce a gas trap which will separate oil and gas from pumping and flowing wells, especially when these wells will flow against but little back pressure, so that such gas may be compressed and put into a pipe line and the oil supplied to suitable tanks; which will maintain a substantially constant low pressure on the gas in the trap so as to prevent the removal of the lighter liquid hydrocarbons from the crude oil; which will provide a storage space of variable capacity the variation in which does not affect the constancy of the pressure maintained; and which will have relief devices which operate when the storage space in its variations reaches a maximum or a minimum, so that the constancy of the pressure is still maintained.

The accompanying drawing illustrates my invention. The single figure of such drawing is a vertical central section through a gas trap embodying my invention.

A fixed tank 10 having a closed bottom is provided with inner side walls 11 and outer side walls 12 which form between them an annular space containing a suitable liquid, such as water 13, into which projects downward the side wall of an inverted floating tank 14, the two tanks 10 and 11 together forming a container of a capacity depending on the height of the floating tank 14.

The fixed tank 10 is suitably supported on a framework 15, and the float tank 14 is guided in the usual manner of gasometers by rollers 16 carried by uprights 17 on a suitable surrounding framework.

An inlet pipe 20 from the well projects upward through the bottom of the tank 10 to a slightly higher level than the no-pressure oil level 21 in such tank, and is provided at its top with an umbrella 22 suitably carried by rods 23 to prevent the oil from the well from splashing through the storage space and to throw such oil downward in the tank 10. A gas outlet pipe 24 also projects up through the bottom of the tank 10, preferably to a greater height than does the pipe 20, and is provided at the top

with an umbrella 25 carried by the upper end of such pipe 24 and stayed by guy wires 26. The umbrella 25 is to make further provision against the splashing of oil into, 60 the gas outlet pipe 24. The pipe 24 below the tank 10 leads to the compressor which pumps the gas into the gas main. A third pipe 27 leads through the bottom of the tank 10, and opens into such tank close to 65 the bottom thereof, for the outlet of oil from such tank. The pipe 27 is turned upward along the outside of the tank 10, and at the no-pressure oil level 21 is provided with a T 28 through which it is connected 70 to a pipe 29 which leads to the oil tanks and to an upwardly extending pipe 30 which is open to the atmosphere so as to prevent the pipes 27 and 29 from forming 75 a siphon. The floating tank 14 is loaded at the top by suitable weights 31 to produce any desired loading, by which a corresponding pressure is produced upon the fluid within the tanks 10 and 14. This loading lowers the oil level from the no-pressure 80 level 21 to a pressure level 32 corresponding to such loading, at which level 32 the hydrostatic pressure of the oil due to the difference between the level 32 and the T 28 (or no-pressure level 21) balances the gas pressure 85 produced on the gas above the oil by the loading 31. In order to maintain the gas pressure constant, the top of the floating tank 14 is provided with a safety valve 33 which is opened by the engagement of its 90 valve stem 34 with a fixed stop 35 when the tank 14 reaches its uppermost limit of movement, said valve being pressed to closed position by a suitable spring 36 and the framework 17 being provided with suitable 95 bumpers 37 for limiting the upward movement of the floating tank 14; and is also provided with a plate 38 directly over the upper end of the pipe 24, which plate 38 100 engages the upper end of the pipe 24 and shuts off the gas outlet through such pipe when the floating tank 14 reaches its lowermost limit of movement, the top of the pipe 24 and the bottom of the plate 38 being suitably finished to produce a substantially 105 tight joint.

In operation, the crude oil and gas from the well flows or is pumped through the pipe 20 into the space within the tanks 10 and 14, and is prevented from splashing 110 by the umbrella 22. This flow is against the gas pressure produced by the loading

31, which is sufficiently slight so that the flow is not interfered with. The oil and gas which enter through the pipe 20 separate on leaving such pipe, the oil falling to the bottom of the tank 10 and the gas filling the space above such oil to the closed top of the floating tank 14. The oil level in the tank 10 is maintained constantly at the level 32, flowing out through the pipes 27 and 29 of the oil tank upon any slight rise in such level. Any fall in the level 32 is prevented by the atmospheric connection 30, so that all siphon action is avoided. The gas above the oil in the tanks 10 and 14 is pumped out through the pipe 24 by the gas compressor into the gas main. This gas is under a constant pressure in the tanks 10 and 14 by reason of the loading 31, which pressure acts on the surface of the oil to maintain the oil level 32. The floating tank 14 rises and falls according as the supply of crude oil and gas through the pipe 20 is greater or less than the outflow of oil and gas through the pipes 27 and 24. If the supply exceeds the outflow too greatly, and the floating tank 14 reaches its upper limit of movement, such tank strikes the bumpers 37 and is prevented from moving farther upward and the valve 33 is opened to permit the escape of excess gas into the atmosphere. If the outflow exceeds the supply too greatly, and the floating tank 14 reaches its lower limit of movement, the plate 38 closes the upper end of the pipe 24 and shuts off the outflow of gas until more has been supplied. The pipes 27 and 28 are preferably sufficiently large so that the oil level 32 is not materially affected by a variation in the rate of supply through the pipe 20. By reason of the constant pressure on the gas and oil within the tanks 10 and 14, the compressor is prevented from developing any partial vacuum within such tanks, and the loss of the lighter hydro-carbons, such as gasolene, from the oil by reason of their being carried off with the gas, and the drawing in of air by reason of any such partial vacuum, are prevented.

I claim as my invention:

1. A gas trap, comprising a fixed tank open at the top and provided with double walls forming between them a space containing a liquid seal, an inverted floating tank the walls of which dip into such liquid seal, a supply pipe leading into said lower tank to supply gas and oil thereto, and two outlet pipes respectively for gas and oil leading from the space inclosed by the two tanks and opening thereinto respectively above and below the oil level therein, said oil outlet pipe extending upward outside the tank to a no-pressure oil level and there being provided with an atmospheric connection, and said floating tank being weighted to produce the desired gas pressure in the space inclosed by the two tanks.

35 sure in the space inclosed by the two tanks.

2. A gas trap, comprising a fixed tank open at the top and provided with double walls forming between them a space containing a liquid seal, an inverted floating tank the walls of which dip into such liquid seal, a supply pipe leading into said lower tank to supply gas and oil thereto, and two outlet pipes respectively for gas and oil leading from the space inclosed by the two tanks and opening thereinto respectively above and below the oil level therein, said oil outlet pipe extending upward outside the tank to a no-pressure oil level and there being provided with an atmospheric connection, and said floating tank being weighted to produce the desired gas pressure in the space inclosed by the two tanks, said supply pipe and said two outlet pipes being fixed in the fixed tank.

3. A gas trap, comprising a fixed tank open at the top and provided with double walls forming between them a space containing a liquid seal, an inverted floating tank the walls of which dip into such liquid seal, a supply pipe leading into said lower tank to supply gas and oil thereto, and two outlet pipes respectively for gas and oil leading from the space inclosed by the two tanks and opening thereinto respectively above and below the oil level therein, said oil outlet pipe extending upward outside the tank to a no-pressure oil level and there being provided with an atmospheric connection, and said floating tank being weighted to produce the desired gas pressure in the space inclosed by the two tanks, said gas outlet pipe being fixed in such fixed tank and projecting upward therein, and said floating tank being provided with a closing plate which closes the upper end of said gas outlet pipe when the float tank reaches its lower limit of movement.

4. A gas trap, comprising a fixed tank open at the top and provided with double walls forming between them a space containing a liquid seal, an inverted floating tank the walls of which dip into such liquid seal, a supply pipe leading into said lower tank to supply gas and oil thereto, and two outlet pipes respectively for gas and oil leading from the space inclosed by the two tanks and opening thereinto respectively above and below the oil level therein, said oil outlet pipe extending upward outside the tank to a no-pressure oil level and there being provided with an atmospheric connection, and said floating tank being weighted to produce the desired gas pressure in the space inclosed by the two tanks, said floating tank being provided with a relief valve which is normally closed but which is opened upon the movement of the floating tank to its upper limit of movement.

5. A gas trap, comprising a fixed tank open at the top and provided with double

walls forming between them a space containing a liquid seal, an inverted floating tank the walls of which dip into such liquid seal, a supply pipe leading into said lower tank to supply gas and oil thereto, two outlet pipes respectively for gas and oil leading from the space inclosed by the two tanks and opening thereto respectively above and below the oil level therein, said oil outlet pipe extending upward outside the tank to a no-pressure oil level and there being provided with an atmospheric connection, and said floating tank being weighted to produce the desired gas pressure in the space inclosed by the two tanks, and means operated by the movement of the floating tank for closing the gas outlet pipe upon the movement of said floating tank to its lower limit of movement.

6. A gas trap, comprising a fixed tank open at the top and provided with double walls forming between them a space containing a liquid seal, an inverted floating tank the walls of which dip into such liquid

seal, a supply pipe leading into said lower tank to supply gas and oil thereto, two outlet pipes respectively for gas and oil leading from the space inclosed by the two tanks and opening thereto respectively above and below the oil level therein, said oil outlet pipe extending upward outside the tank to a no-pressure oil level and there being provided with an atmospheric connection, and said floating tank being weighted to produce the desired gas pressure in the space inclosed by the two tanks, and means for closing the gas outlet pipe upon the movement of the floating tank to its lower limit of movement and for permitting the escape of gas from the space within the two tanks when the floating tank reaches its upper limit of movement.

In witness whereof, I have hereunto set my hand at Taft, Cal., this 25th day of July, A. D. one thousand nine hundred and sixteen.

CHARLES C. SCHARPENBERG.
